UNITED STATES PATENT OFFICE.

KATHLYN GOLAIS, OF NEW YORK, N. Y.

CORSET.

SPECIFICATION forming part of Letters Patent No. 759,266, dated May 10, 1904.

Application filed May 15, 1902. Serial No. 107,475. (No model.)

To all whom it may concern:

Be it known that I, KATHLYN GOLAIS, a citizen of the United States, residing at New York, in the county of New York and State of New York, have invented certain new and useful Improvements in Corsets; and I do hereby declare the following to be a full, clear, and exact description of the invention, such as will enable others skilled in the art to which it applies to make and use the same.

It is the object of my invention to produce a corset that shall be convertible at will from a firm inelastic corset into one that will readily yield to the movements of the body and expand to permit full and deep breathing.

It is well known that singers, elocutionists, actresses, and the like experience great difficulty in being fitted with a corset that will hold the proper lines at all times and yet allow of the free movement of the body and of the deep full breathing indispensable to their professional duties. Many such persons find it necessary to change the ordinary non-elastic corset for a flexible or elastic waist or bodice prior to a performance and afterward to reassume the ordinary corset for the reception-room or street, because of the diametric properties adapted to the one occasion, but not suited to the other. This entails a great amount of time and inconvenience and is then far from satisfactory in results. By my invention I have in one corset embodied to the highest perfection the distinctive features of each, rendering the corset firm and inelastic or yielding and elastic instantly at will. My invention also renders the corset pliable and yielding, so that the wearer may lounge about or resume a recumbent position with perfect comfort.

It will be understood that an ordinary corset of any favored style or shape may be readily altered to embody my improvement at a slight expense. This I accomplish by means of the peculiarities of construction and arrangement of parts hereinafter set out and claimed and as illustrated in the accompanying drawings, in which—

Figure 1 is a front view of a corset embodying my invention. Fig. 2 is a rear view. Fig. 3 is an enlarged detail view from the inside

showing the means by which the corset is rendered inelastic or yielding.

In the drawings, A represents a corset of any desired style provided with the usual stays B, fastened in front by the usual means C and in the rear by the ordinary lacing D. Preferably at each side of the central front I insert elastic webbing E, either as a continuous piece in the form of a gusset or in transverse strips secured to the body portion of the corset at each side, as shown.

F represents a flap of non-yielding fabric or other material which is permanently stitched to one side of the corset-body, as at G, and underlies the elastic portion, extending to and beyond the opposite edge H of the corset-body. Upon the free edge of this flap F are secured clasp-studs J, similar to those ordinarily used on gloves, and on the inner side of the corresponding corset edge H are the clasps I. In use as a non-elastic corset the clasps I are engaged with the studs J, thus firmly uniting the flap F with the corset edge H and bridging the opening beneath the webbing E with non-yielding material, which takes the strain from the elastic E and constitutes a firm non-yielding front. When it is desired to allow of expansion, the clasps are unfastened, the shirred lace trimming K at the top of the corset gives, and the strain comes upon the elastic, which yields readily to the expansion of the lungs in breathing and lends pliability to the garment, allowing of free movement.

In the back, at either side of the center, I also preferably provide elastic gussets L, which may or may not be provided with underlying fabric M, stitched at both sides to the corset-body and having sufficient fullness to allow the elastic webbing full expansion. If desired, I may also provide elastic gussets approximately midway of the central front and the hips, as shown at N, or in any other place where it is desired to permit of expansion of the abdominal portion of the corset, and thus secure pliability. The underlying material of such gussets may be fitted with clasps, as shown in the central front portion, which in many cases is desirable, or the non-elastic material may be stitched at both

sides, allowing the necessary fullness to permit the expansion of the elastic.

When the clasps I and J are fastened, the corset is to all practical intents and purposes 5 the same as the ordinary stylish article, firmly supporting the form, with the modicum of expansion allowed by the elastic gussets in the back. A singer, for instance, may wear the corset to the theater or reception 10 with the full consciousness that she is modishly dressed and presents a trim appearance, and then when her turn comes to sing or perform other analogous duty she may unobserved loosen the clasp by inserting a 15 finger beneath the bodice without retiring to a dressing-room or requiring the assistance of a maid.

I am aware that it is not new to provide 20 insertions of elastic in corsets to permit expansion; but in all such cases known to me the elastic at all times sustains the strain and soon becomes flaccid and useless, as well as unsightly. Moreover, I am not aware that any one has ever used my convertible feature 25 whereby the corset is allowed to expand when desired and held firm when desired.

It will be understood that my convertible 30 elastic gusset, having the underlying detachably-secured non-elastic flaps, may be employed with or without the supplemental elastic gussets in other locations, as mentioned. It will be likewise obvious that many 35 changes may be made in details of arrangement and construction without departing from the spirit of my invention as described and claimed, wherefore I do not desire to be limited to the specific construction shown.

Having thus fully described my invention, what I claim as new, and desire to secure by 40 Letters Patent of the United States, is—

1. A corset having in the central front portion gores bridged by elastic and an underlying flap of non-elastic material secured at one side of the corset-body and its free edge 45 extending beyond and removably secured by suitable fastening means to the other side of the opening, in the central back and in the abdominal portion other gores bridged by elastic, substantially as described.

50 2. In a corset, gores extending from approximately the waist-line upward and adapted for the insertion of elastic, an underlying flap or guard of non-yielding material stitched to the corset-body at one side and extending 55 beyond the opposite side of the gore, means whereby the free edges of the flap are re-

movably secured to the corset and gores formed in the abdominal portion of said corset below the waist-line, substantially as described.

60

3. In a convertible corset, the combination with an elastic bridged gore or opening extending from approximately the waist-line upward, of an underlying, non-elastic flap 65 stitched to one side of the opening and its free end extending beyond the opposite side and secured thereto by readily-detachable fastening means, whereby the non-elastic flap will receive any strain and prevent expansion when fastened, and, when unfastened, will permit 70 of expansion for unimpeded, deep and full breathing, gores formed in the abdominal portion of said corset below the waist-line thereof, and elastic or extensible means for yieldingly closing said gores, substantially as described.

75

4. A corset having in the central front portion gores extending from approximately the waist-line upward and bridged by an elastic and an underlying flap of non-elastic material 80 secured at one side to the corset-body and its free edge extending beyond and removably secured by suitable fastening means to the other side of the opening, in the central back and in the abdominal portion other gores 85 bridged by elastic, substantially as described.

5. A corset having gores formed therein in the front and rear sections from the waist-line upward and in the front sections from the waist-line downward, elastic means normally 90 tending to close said gores and means imposed thereunder detachable from one side for limiting the extension of said elastic and constructed to relieve the tension thereon, substantially as described.

95

6. A corset having gores formed therein in the front and rear sections thereof from the waist-line upward and in the front sections thereof from the waist-line downward, elastic means normally tending to close said gores and an inelastic flap attached to one side of said gores and carrying on its free end means to coöperate with fastening means on the opposite side of said gore, arranged to relieve the tension on said elastic means, substantially as 100 described.
